UNITED STATES PATENT OFFICE.

JEAN W. BICKS, OF CHICAGO, ILLINOIS, ASSIGNOR TO WESTERN PRODUCTS COMPANY,
OF CHICAGO, ILLINOIS, A CORPORATION OF ILLINOIS.

DESIGN FOR A BOTTLE.

Application filed February 9, 1928. Serial No. 25,310. Term of patent 3½ years.

To all whom it may concern:

Be it known that I, JEAN W. BICKS, a citizen of the United States, residing at Chicago, in the county of Cook and State of Illinois, have invented a new, original, and ornamental Design for Bottles, of which the following is a specification, reference being had to the accompanying drawing, forming part thereof.

The Figures 1 and 2 are front and end views respectively of the bottle, showing my new design.

I claim:

The ornamental design for a bottle, as shown.

In testimony whereof I affix my signature.

JEAN W. BICKS.
